UNITED STATES PATENT OFFICE.

JOHANNES A. M. TRAUTS, OF ROTTERDAM, NETHERLANDS.

ELECTRIC LAMP SWITCH.

1,075,953.

Specification of Letters Patent.

Patented Oct. 14, 1913.

Application filed January 24, 1911. Serial No. 604,380.

To all whom it may concern:

Be it known that I, JOHANNES ADRIANUS MARINUS TRAUTS, a subject of the Queen of the Netherlands, residing at 10 Boerenwischmarkt, Rotterdam, Kingdom of the Netherlands, have invented certain new and useful Improvements in and Relating to Electric Lamp Switches, of which the following is a specification.

10 This invention relates to electric lamp switches of the type in which the power circuit is closed and broken in the switch by means of contacts, extending into a rocking sealed glass tube or container, which are connected or disconnected by means of mercury, the switch itself being operated by small currents in a circuit independent of the main or working circuit and closed and broken in known manner by a key suited to small currents.

20 According to the present invention the arrangement is such that successive momentary excitations of an electromagnet provided with an armature result in alternate 25 rockings of the container, so that current either flows continuously or ceases to flow in the work circuit, whereas in the low tension circuit current only flows during the actual 30 operation of completing or breaking the work circuit.

The manner of adjustment of the mercury contact tube by cams or cam disks permits the switch to be easily constructed as a series switch, several mercury contacts being 35 arranged in proximity, all of which can be so controlled by electromagnets that the desired changes of connection are effected.

In the accompanying drawing one form of construction of the new switch is illustrated 40 by way of example.

Figure 1 is a front elevation, and Fig. 2 a rear elevation of the switch partly in section. Fig. 3 is a plan. Fig. 4 a diagrammatic view of a complete installation, while 45 Figs. 5 to 8 are diagrammatic views of a series switch.

The switch is mounted upon a base plate 1 of insulating material. Upon this plate is secured an electromagnet, the core 2 of which 50 is fastened to the plate while the coil 3 rests upon it. At its upper end the core carries two metal pieces 4 between which is revolvably arranged an armature 5. Connected to this armature 5 is a pin 6 on the end of which is pivoted a two-armed pawl 7.

Near the coil 3 (Fig. 3) a spindle 8 is se-

cured in bearings upon the plate 1. This carries on one side a toothed wheel 9 with four teeth or pins which are shifted by the two-armed pawl 7. A small locking pawl 10 prevents backward movement of the toothed wheel 9. Upon the other end of the spindle 8 is secured an elliptical disk 11.

Behind the coil 3 (Fig. 3) there is mounted in bearings a small spindle 12 upon which a plate 13 is rotatably fastened. This carries in a sheath 14 of insulating material a sealed evacuated glass tube 15 containing some mercury. Two platinum wires extend into the interior of the glass tube from one side, these being sealed into the glass, while outside the tube they are connected by flexible conductors to the terminals 16 and 17. Two other terminals 18 and 19 on the switch serve for the introduction of current to the magnet coil. The plate 13 rests upon the elliptical disk 11.

As may be seen from Fig. 4, the switch 20 is advantageously arranged in the corner of the floor above the room, and the battery 21 forming the source of the small current may also be near the switch so that both these devices are always readily accessible. The power conductors are led in the usual manner through the ceiling to the lamp 22 while the conductors for the small current pass from the switch 20 to the battery 21 and to the switch 23.

The new switch operates as follows: The electrodes of the weak current battery 21 are connected with the terminals 18 and 19 of the switch with the switch 23 in circuit and the power supply wires are joined to the terminals 16 and 17. If now the electromagnet is momentarily excited through the small current circuit being closed by operation of switch 23, the armature 5 will be attracted and will rotate about its axis until its end rests upon the magnet core. By this means the pin 6 and pawl 7 will be raised so that the pawl is moved toward the right (Fig. 2). The upper arm of the pawl which is resting against a tooth will turn the toothed wheel 9 while the lower arm comes into contact with the next two following teeth of the wheel. The wheel will therefore be held in a position in which the locking pawl 10 may engage another tooth (Figs. 1 and 2). While the toothed wheel has turned through the space of one tooth, the elliptical disk 11 will have turned 90° from the position shown in Fig. 1. The plate 13 with the

glass tube then takes the sloping position shown in Fig. 2 in which the mercury flows from the one end of the tube to the other and makes connection between the two platinum wires, thus the lamp is switched in. The exciting circuit (the small current circuit) is now again interrupted and the armature falls back into the position shown in Fig. 1, the pin 6 and pawl 7 moving freely back so that the upper arm of the pawl 7 engages behind the next tooth, while the glass tube remains in its new position. If the electromagnet is momentarily excited a second time the disk 11 will be turned 90° farther and the glass tube inclined to the other side so that the mercury will flow back to the left (Fig. 1); contact between the platinum wires will be interrupted and the lamp will be extinguished.

20 If the new stitch is to be used for a series connection of lamps or for a series of lamps, two or more disks 11 will be arranged one beside another upon the spindle 8. These are then, however, formed as quadrants 24 and 25 and are relatively staggered upon the spindle 8 (Fig. 5). Upon each of these disks rests a mercury contact tube 15. The quadrants 24 and 25 may be so arranged that in a certain position both lamps or groups of lamps are cut out (Fig. 5). If the spindle is thereupon turned 90° one group of lamps alone is lighted (Fig. 6); upon a further turn through 90° this group of lamps remains alight and the other group of lamps is connected in (Fig. 7). Upon still further revolution the first group of lamps is switched out while the other remains in circuit (Fig.

8), while finally on further revolution the second group is also extinguished (Fig. 5).

What I claim is:

1. An electric switch comprising a cam shaft, cam-like means thereon, a toothed wheel on said shaft having teeth 90° apart, an electromagnet, an armature for the same, a two-armed pawl secured to the armature, and coöperating with three teeth of the wheel, and a liquid contact maker arranged to be operated by the cam.

2. An electric switch comprising a cam shaft, a cam thereon having maximum and minimum radii 90° apart, a toothed wheel on said shaft having teeth 90° apart, an electromagnet, an armature for the same, a two-armed pawl secured to the armature, and coöperating with three teeth of the wheel, and a liquid contact maker arranged to be operated by the cam.

3. An electric switch comprising a cam shaft, a cam thereon having maximum and minimum radii 90° apart, a toothed wheel on said shaft having teeth 90° apart, an electromagnet, a low voltage, electric supply for same, a pivoted armature for said magnet, a two-armed pawl secured to the armature and coöperating with three teeth of the wheel and a liquid contact maker arranged to be operated by the cam.

In testimony whereof I have hereunto set my hand in presence of two subscribing witnesses.

JOHANNES A. M. TRAUS.
